Inventor
Dx,

By J. Hume Talbert, Attorney

UNITED STATES PATENT OFFICE.

DILLARD H. COX, OF SEASIDE, OREGON.

LOGGING-HOOK.

1,376,258.

Specification of Letters Patent. Patented Apr. 26, 1921.

Application filed February 11, 1919. Serial No. 276,233.

To all whom it may concern:

Be it known that I, DILLARD H. Cox, a citizen of the United States of America, residing at Seaside, in the county of Clatsop and State of Oregon, have invented new and useful Improvements in Logging-Hooks, of which the following is a specification.

The object of the invention is to provide a new and novel form of hook to be used particularly by lumber men and persons engaged in similar work where it is necessary to maintain the hook connected with grapple chains or similar devices, despite whether the hoisting machine rope becomes slack or not. To this end the invention comprises a body having a hook formed therewith and a keeper for the hook, the keeper being engaged by the thumb latch mounted in the body, but not exposed above the surface thereof, so that there is no danger of accidental displacement of the latch which will permit its releasing the keeper.

The invention is illustrated and described in a specific embodiment to which, however, it is not to be restricted. The writer reserves to make such changes or alterations as the actual reduction to practice may suggest, in so far as such changes or alterations are compatible in spirit with the annexed claim.

In the accompanying drawings:

Figure 1 is a perspective view of the improved hook.

Fig. 2 is a longitudinal sectional view.

Fig. 3 is a transverse sectional view on the line 3-3 of Fig. 1.

Referring to the drawings, the invention is shown as comprising a body portion 1 formed integral with which there is a hook 2, the latter terminating in a nose 3 of wedge-shape conformation and reduced both in thickness and width at the base of the wedge where it connects with the main portion of the hook.

The body portion 1 is formed with an eye 4 extending transversely through the same and this body provides means for an attachment of a hoisting machine or rope to the device.

A keeper 5 is employed to close the hook and prevent its disconnection from a machine to which it may be attached. This keeper is pivotally mounted on the body portion and is provided with a relatively thin disklike shank 6 which lies within a slot

7 formed in the body portion directly below the hook. A pintle 8 is mounted transversely in the body portion and crosses the slot 7, passing also through the shank 6 at 60 the center of the latter, the engagement between the shank and the pintle, however, being loose enough to permit it and the keeper to be swung away from or against the hook. The keeper is formed with a 65 pocket 9 in which the nose 3 engages when the keeper is in the position of closure for the hook and the keeper is further provided with a clearance notch or recess 10 for the said nose when it, the keeper, is swung away 70 from the hook.

To positively maintain the keeper in the position of closure, the body 1 adjacent the eye 4 is counter-sunk as at 11 and is further formed with a rectangular hole 12 opening 75 on the other side of the body from the counter-sunk portion but communicating with the latter. The counter-sinking extends to the slot 7. Therefore the rectangular hole just crosses the said slot. The shank 6 is 80 made of such diameter that its edge protrudes into one side of the hole 12 and this edge is notched as at 13, the notch leaving the rectangular hole 12 clear when the keeper is closed in position. A rectangular 85 shaped block 14 conforming to the hole is formed with a shank 15 and this block rests in the hole and its shank passes through into the counter-bore 11 in which there is received a spring 16 which is compressed 90 between the bottom of the counter-bore and a head or cap 17 attached to the upper end of the shank 15. When the keeper is in the position of closure, the block 14 may engage 95 in the notch 13 and the keeper will thus be prevented from swinging away from the hook, but when the head 17 is depressed the block is forced downward or laterally away from the notch 13 whereon the keeper may be swung backwardly away from the hook 100 to permit the disengagement of the hook from anything to which it may be attached.

That end of the block which connects with the shank in the open position of the keeper bears against the side of the disk or shank 105 6 but when the keeper is swung to closed position this block is permitted to enter the notch 13 and retain the keeper in such closed position. With the keeper in closed position the head 17 lies flush with the adjacent side of the body 1 so that there is no danger of the keeper being released by accidental

contact or impact with some outside object. When the keeper is released, the head is depressed into the counter-bore and the block is forced away from the shank 6 releasing 5 the latter when it is lower, or its free end lies flush with the opposite side of the body 1.

From the foregoing description and the accompanying drawings, it is believed that a clear enough understanding of the invention 10 is to be had to render further description unnecessary.

The invention having been described what is claimed as new and useful, is:

A device of the kind described comprising 15 a body formed with a hook and having a slot, a keeper for the hook having a disk-like shank lying in said slot, a pintle mount-

ed in the body and crossing the slot and pivotally engaging the said disk-like shank, the said shank being formed with a notch, 20 the body being formed on one side with a rectangular slot and on the other side with a counterbore connecting with said slot, a rectangular-shaped latch element mounted in the rectangular slot and engaging with 25 the notch in the shank when the keeper is in closed position for the hook, and a spring disposed in the counterbore and operatively connected with the latch to normally move the latter into engagement with a notch in 30 the shank.

In testimony whereof I affix my signature.

DILLARD H. COX.
